US00D785631S

(12) **United States Design Patent** (10) **Patent No.:** **US D785,631 S**
(45) **Date of Patent:** **** May 2, 2017**

(54) **IMAGE SENSOR**

(71) Applicant: **MITSUBISHI ELECTRIC CORPORATION**, Tokyo (JP)

(72) Inventors: **Akiko Fujiuchi**, Tokyo (JP); **Atsushi Ito**, Tokyo (JP); **Kazuya Makabe**, Tokyo (JP); **Masaki Wakisaka**, Tokyo (JP)

(73) Assignee: **Mitsubishi Electric Corporation**, Tokyo (JP)

(**) Term: **15 Years**

(21) Appl. No.: **29/548,638**

(22) Filed: **Dec. 15, 2015**

(30) **Foreign Application Priority Data**

Jun. 18, 2015 (JP) 2015-013493

(51) LOC (10) Cl. **14-02**

(52) U.S. Cl.
